CLAIM

The ornamental design for a vehicle exterior, toy and/or replica thereof, as shown and described.

DESCRIPTION

FIG. 1 is a front elevational view of a vehicle exterior, toy and/or replica thereof showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a top, front, and left side perspective view thereof; and,

FIG. 7 is a top, rear, and left side perspective view thereof. The half tonal portions and broken lines represent portions of the vehicle exterior, toy and/or replica thereof that form no part of the claimed design.

1 Claim, 7 Drawing Sheets
